FRANK E. CROTTO, OF DALLAS, TEXAS, ASSIGNOR OF ONE-HALF TO SAMUEL FRESHMAN, OF DALLAS, TEXAS.

AUTOMATIC AIR-CONTROLLING DEVICE.

1,172,438.

Specification of Letters Patent.

Patented Feb. 22, 1916.

Application filed September 4, 1914. Serial No. 860,179.

To all whom it may concern:

Be it known that I, FRANK E. CROTTO, of Dallas, Texas, residing at 1819 Bennett street, have invented certain new and useful Improvements in Automatic Air-Controlling Devices, of which the following is a specification.

This invention as specified relates to new and useful improvements in automatic air controlling device and has as its primary object the production of a machine which will furnish an air supply at a constant and unvarying pressure.

An object of the invention is to provide an automatic air controlling device embodying a balanced and floating air bell, said element being contained and guided within a liquid shell and hermetically sealed therein.

Another object is to provide an automatic air controlling device embodying a high and low pressure reservoir and means for controlling the passage of the air from the high pressure reservoir to the low pressure reservoir.

Still another object is to provide a machine positively and automatically controlled, in the maintenance of its air supply, through the medium of a liquid balance control.

Finally with these and other objects in view the invention has relation to a certain arrangement and combination of parts, an example of which is described in this specification, illustrated in the accompanying drawings and pointed out in the appended claims.

Figure 1 is a vertical longitudinal sectional view of the assembled machine. Fig. 2 is a partial view of the upper portion of a float chamber and correlated elements which are embodied in the invention. Fig. 3 is a plan view of a certain actuating member embodied in the invention, the view being taken upon the section line A—A of Fig. 1. Fig. 4 is a longitudinal sectional view of a vertical guide tube correlated with the air bell.

Referring now more in particular to the drawings, the numeral 1 designates an outer shell which is adapted to contain and house elements hereinafter mentioned. A high pressure storage reservoir 2 is contained within the shell 1. Said reservoir is centrally

provided with a permanent and fixed guide tube 3, said guide tube having its upper extremity open. The lower extremity of said guide tube has connection with an air discharge pipe 4 which, as may here be understood, is adapted to convey to and furnish a carbureter, (not shown) with which this compressor is adapted to associate, an unvarying and reliable pressure supply. The open annular space between the shell and reservoir 2 is filled with a non-volatile liquid, as illustrated. An air bell or low pressure reservoir 5 is contained within the upper portion of the shell. Said low pressure reservoir, as illustrated, has its lower portion open and immersed and hermetically sealed in the liquid above referred to. The bell or reservoir 5 is weighted as indicated by the numeral 6, which, as will be seen, subjects said reservoir to a sufficient downward pressure for compressing the air within said reservoir to a sufficient pressure for delivery to the carbureter. As illustrated the construction of the high and low pressure reservoirs is such as to be most efficient and strong, as the heads of same are formed dome shaped and adapted to closely fit one in the other when the bell is in a downwardly limited position.

A perforated guide tube 7, having its lower depending extremity open and fitting within the associate guide tube 3, is substantially carried by the head of the bell 6. Fig. 4 is a longitudinal sectional view of said guide tube which illustrates elements correlated therewith not shown in Fig. 1. A tube 8 is carried within the guide tube 7 and sealed on its lower extremity; said tube extends through the cap 9 of the guide and is provided with a cap 10. A pull rod 11 provided on its lower extremity with a head 12 is confined within the tube 8 and extends through a loose fitting hole in the cap 10 and provided with a slotted yoke 13 fixed to its upper extremity. As later seen the correlated tubes are adapted to undergo a vertical displacement due to the rise and fall of the low pressure reservoir; such action will allow the pull rod to remain stationary while the tubes slowly travel therewith. Reference being had to the arrows in Fig. 4 it is clearly seen how the air may pass from the low pressure reservoir through the perforations of tube 7 downward into

the guide tube 3 into the discharge pipe 4 without escaping to atmosphere where the pull rod 11 emerges to atmosphere; such is the function of the sealed tube 8.

5 An inverted pressure drum 14 is contained within the high pressure reservoir and communicates directly with a tube 15 which extends from the reservoir and extends vertically upward where it communicates with a float chamber 16. As illustrated the pressure drum, float chamber, and connecting pipe 15, contain a liquid, preferably a non-volatile liquid such as used in the shell. The purpose of the liquids embodied in the machine is merely to assist and facilitate the functions of the operation, and as permanency is desired a non-evaporating liquid is employed. As seen the liquid in the two elements 14 and 16 stand 10 at unequal level, obviously a pressure is affecting the equilibrium of the liquid, a description of which will be later given.

A float 17 is contained within the float chamber and buoyed upon the liquid surface; 25 said float through the medium of its correlated elements is adapted to automatically govern the action and period of operation of the machine. A vertical rod 18 is fixed to the upper end of the float and extends 30 through a fiber insulating cover cap 19 of the float chamber. It is here to be understood that the float member is employed to open and close an electric circuit, said circuit in turn mechanically maintaining a 35 pressure within the reservoir 2. To this end a pair of adjacent mercury cups 20 are disposed upon the base or cover 19. A circuit line C is here cut and the terminal of each connected to the mercury cups and conducted 40 to the mercury therein. Said circuit is adapted to be led to a motor (not shown) employed in connection with the machine. A bracket 21 insulated from and fixed to the rod 18 carries a pair of depending dip rods 45 22 adapted to be immersed in the mercury cups thereby closing the circuit C. A support bracket 23 is fixed to the fiber base and pivotally carries an actuating member 24 which lies in close contact with the rod 18 50 and between a pair of collars 25 fixed to the rod. A coiled tension spring 26 is fixed to the support and actuating member and adapted to exert a pull upon the actuating member, the purpose of which will later develop 55 in the description of the operation of the machine.

It will here be understood that a moderately high pressure will be maintained in the reservoir 2 and to this end and in this instance a centrifugal blower B through a connecting pipe 27 is employed to maintain a pressure supply to the reservoir 2. A check valve 28 is embodied in the line 27 to check and prevent the backing up of the pressure through said pipe 27.

It will be necessary to furnish means for controlling the admission of the pressure from the reservoir 2 to the low pressure reservoir 5. To this end a pressure control line 29 is employed, said line has embodied therein automatic control means directly correlated with the pull rod of the low pressure reservoir. The action of the reservoir will then exercise a controlling relation over the passage of the air through the line 29. The line 29 opens directly into the reservoir 2, extends therefrom where it opens into a check valve 30 and liquid control valve 31, said control valve consists of a pair of parallel tubes 31 associated with a connecting chamber 32 which forms a substantial U shaped element. A filler plug 33 is provided from which the control valve may be filled with a nonvolatile liquid, such as oil. The line 29, as mentioned, embodies this element; 75 the pressure control line 29 has connection with a T member of the control valve and leads therefrom passing upwardly through the reservoir 2 and opening directly within and beneath the low pressure reservoir. 90

A valve trip member 34 in the form of a U shaped rod, is contained within the control valve and has one of its extremities normally in contact or just beneath the lower side of the check of valve 30. The other extremity of the valve trip member extends upwardly through the control valve and is provided with a slotted yoke 35 similar to the one 13 previously mentioned. A lever 36 having its extremities loosely confined within the slotted yokes 13 and 35 is pivoted at 37 upon the shell 1 and establishes a movable and controlling relation of the pull rod 11 over the trip member 34. A support bracket 38 having similar functions to the one 23 is substantially carried by the uppermost extremity of the control valve. Said bracket is provided with a pivoted actuating member 39 and pull spring 40. The actuating member 39 is confined between a pair of 100 collars 39^a fixed to the rod 34. The spring 40 is attached to the member 39 and has its other extremity provided with a threaded member 41 and thumb nut 42, such an arrangement gives an adjustable means for 110 varying the tension of the spring. 115

An assembly has been given of the controlling element embodied in the pressure control line; the direction of the pressure flow, through said line 29, will now be clearly traced. The arrows indicate the pressure leaving the reservoir 2 through the line 29, at the proper time of flow the check valve 30 will be tripped allowing the pressure to pass downward against the liquid in the control valve. The liquid will immediately divert the pressure into the line 29 which connects with the T member, the line 29 then carries the pressure directly to the reservoir 5. The function of the oil control valve is then 130

clearly to furnish a means to allow the valve trip member a free and unrestricted movement within the control valve and divert the pressure into the proper channel without the 5 employment of stuffing boxes and the like.

A description of the operation will now be given, and beginning with the machine in its normal and poised operating position. A moderately high pressure has been set 10 up in the reservoir 5 through the medium of the centrifugal blower. Said pressure is acting directly downward upon the liquid contained in the pressure drum 14 which forces the liquid in the float chamber upward breaking the circuit C and stopping the operation of the blower. When the float began to rise and draw the dip rods 15 22 from the mercury cups the spring 26 executed a quick and positive upward jerk 20 of the correlated elements which prevented the arcing and hesitancy of the break in the circuit. The air bell or low pressure reservoir 5 is feeding its pressure through the various channels, as previously described, 25 into the discharge pipe 4. The weighted reservoir 5 will slowly descend keeping up the flow at a constant pressure. When the bell descends to its lower-most position the pull rod 11 through its head 12 will exert a 30 downward pull on the lever 36 which will raise the trip rod in the control valve thereby opening the valve 30. Here the pull spring 40 performs substantially the same functions as the spring 26, that is, 35 the valve 30 is equally lifted when the action starts. The air pressure flow then takes the direction as described, exhausting the high pressure from reservoir 2 to reservoir 5. This immediately causes the reservoir 5 to slowly return to its normally upward limited position. At this stage of the 40 operation (the pressure being exhausted from the reservoir 2) the liquid in the pressure drum and float chamber will seek their 45 level which allows the float to drop; this immediately closes the circuit which causes the blower to again perform its function of raising the pressure in the reservoir 2. When the pressure is raised sufficiently high 50 in the reservoir 5 the float 17 will open the circuit thereby stopping the motor till the traveling air bell again effects the controlling elements in the manner described which will again set the machine in operation 55 repeating the cycle of action substantially, as illustrated and described.

The invention is presented as including all such modifications and changes as may properly come within the scope of the following claims.

Claims:

1. In an automatic air controlling device, the combination of an outer shell, a high pressure reservoir contained within said shell, a low pressure reservoir contained

within said shell, a guide tube carried within the high pressure reservoir, a perforated guide tube carried by the low pressure reservoir and having its lower extremity confined within the first guide tube 70 mentioned and means for controlling the passage of air from high pressure to low pressure reservoir.

2. In an automatic air controlling device, the combination of an outer shell, a high 75 pressure reservoir contained within said shell, a low pressure reservoir contained within said shell, a perforated guide tube correlated with the low pressure reservoir, a sealed tube contained within the perforated tube, a pull rod slidably confined within the sealed tube, a guide tube carried within the high pressure reservoir, the perforated guide tube of the low pressure reservoir slidably confined within the guide 80 tube of the high pressure reservoir and means provided for controlling the air passage from the high pressure to the low pressure reservoir.

3. In an automatic air controlling device, 90 the combination of an outer shell, a high pressure reservoir contained within said shell, an annular liquid receptacle formed between two said elements recited, guide tube within the reservoir, a discharge line 95 connected with the guide tube, a floating air bell poised above the reservoir and having its lower open extremity hermetically sealed in the liquid contained in the annular space and a control valve.

4. In an automatic air controlling device, the combination of an outer shell, a high pressure reservoir contained within the shell, an annular liquid receptacle formed between two said elements recited, a guide 105 tube within the reservoir, a discharge line connected with the guide tube, a floating air bell poised above the reservoir and having its lower open extremity hermetically sealed in the liquid contained in the annular space, a pressure drum within the high pressure chamber, a float chamber correlated with the pressure drum and means correlated with float chamber for controlling the passage of air from the reservoir 110 to the air bell.

5. In an automatic air controlling device, the combination of an outer shell, a high pressure reservoir contained within the shell, a low pressure reservoir contained in 120 the shell, a pressure control line opening into the high pressure reservoir and communicating with the low pressure reservoir and a control valve embodied in the pressure control line adapted to control the 125 passage of air through said line from the high pressure reservoir to the low pressure reservoir.

6. In an automatic air controlling device, the combination of an outer shell, a high 130

- 41 pressure reservoir contained within the shell, a low pressure reservoir contained within the shell, a guide tube within the high pressure reservoir, a perforated guide tube carried by the low pressure reservoir and confined in the first guide tube, a pressure control line connecting the two reservoirs, a control valve embodied in the pressure control line and means for controlling the flow of air through the said control line. 70
- 5 7. In an automatic air controlling device, the combination of an outer shell, a high pressure reservoir contained within the shell, a low pressure reservoir contained within the shell, a guide tube within the high pressure reservoir, a perforated guide tube carried by the low pressure reservoir and confined in the first guide tube, a pressure control line connecting the reservoirs, 75
- 10 a control valve embodied in the pressure control line, and a valve trip member contained within the control valve and adapted to control the flow of pressure through the control valve. 80
- 15 29 8. In an automatic air controlling device, the combination of an outer shell, a high pressure reservoir contained within the shell, a low pressure reservoir contained within the shell, a guide tube within the high pressure reservoir, a perforated guide tube carried by the low pressure reservoir and confined in the first guide tube, a pressure control line connecting the two reservoirs, control valve embodied in the pressure control line, and a valve trip member contained within the control valve and a lever correlated with the low pressure reservoir and the valve trip member. 85
- 20 35 9. In an automatic air controlling device, the combination of an outer shell, a high pressure reservoir contained within said shell, a low pressure reservoir contained within said shell, a pressure drum correlated with one of the reservoirs, a float chamber connected with the pressure drum, a float within said chamber, a pressure control line connecting the two reservoirs, a control valve embodied in the pressure control line, a check valve embodied in the control valve, means for operating the check valve and an electrical circuit breaker correlated with the float chamber. 90
- 25 40 10. In an automatic air controlling device, the combination of an outer shell, a high pressure reservoir contained within said shell, a low pressure reservoir contained in said shell, a pressure drum correlated with one of the reservoirs, a float chamber connecting with said pressure drum, a float within said chamber, a pressure control line connecting the two reservoirs, a control valve embodied in the pressure control line, a check valve embodied in the control valve, a valve trip member within the control valve and adapted to trip the check valve, a liquor filler plug correlated with the valve, and means for establishing a controlling relation of the pressure drum over the trip rod. 95
- 30 35 11. In an automatic air controlling device, the combination of an outer shell, a high pressure reservoir contained in said shell, a low pressure reservoir contained in said shell, a pressure drum contained within one of the reservoirs, a float chamber connecting with the pressure drum, a float within said chamber, a pressure control line connecting the two reservoirs, a control valve embodied in the pressure control line, a check valve embodied in the control valve, a valve trip member within the valve, a liquor filler plug correlated with the control valve, an actuating member adapted to exercise a lifting relation over the trip rod, means for establishing a controlling relation of the pressure drum over the trip rod and a circuit opener correlated with the float. 100
- 35 40 12. In an automatic air controlling device, the combination of an outer shell, a high pressure reservoir contained in the shell, a low pressure reservoir contained in the shell, a pressure control tube connecting the two reservoirs, a pressure drum correlated with one of the reservoirs, a float chamber connecting with pressure drum, a float contained in said chamber, a vertical rod carried by the float, dip rods carried by said vertical rod, mercury cups adapted to receive the dip rods, and a pivoted actuating member adapted to lift the dip rods. 105
- 40 45 13. In an automatic air controlling device, the combination of an outer shell, a high pressure reservoir contained within said shell, a low pressure reservoir contained within said shell, a pressure control tube connecting with the high pressure reservoir, a valve embodied in the pressure control tube, a filler plug provided in the control valve casing above the liquid level, and communicating with the low pressure reservoir. 110
- 45 50 14. In an automatic air controlling device, the combination of an outer shell, a high pressure reservoir contained in said shell, a low pressure reservoir contained in said shell, a pressure control line connecting the two reservoirs, a control valve embodied in the pressure control line, liquid contained in the control valve, a check valve embodied in the control valve, and a valve trip rod confined in the liquid of the control valve and adapted to trip the said check valve. 115
- 50 55 15. In an automatic air controlling device, the combination of an outer shell, a high pressure reservoir and low pressure reservoir contained in the shell, an annular space formed between the shell and one reservoir, the other reservoir having its lower open end extending into said annular space, each reservoir provided with guide tubes, 120
- 55 60 65 125
- 60 65 130

said tubes correlated one with the other, a hermetically sealed tube confined in one of the guide tubes, means provided for controlling the passage of air from one reservoir 5 to the other and a pull rod confined in one of the said guide tubes adapted to control the above recited air control means.

In testimony whereof, I affix my signature in the presence of two witnesses.

FRANK E. CROTON.
